UNITED STATES PATENT OFFICE

MAX KRISSIEP, OF WYOMISSING, PENNSYLVANIA, ASSIGNOR TO TEXTILE MACHINE WORKS, OF WYOMISSING, PENNSYLVANIA, A CORPORATION OF PENNSYLVANIA

AUTOMATIC STOP MECHANISM FOR BRAIDING MACHINES

Application filed September 26, 1930. Serial No. 484,687.

My invention consists in improved automatic stop mechanism adapted particularly for braiding machines; and it provides in its full embodiment for effecting automatic stopping either in case of the breaking of a thread as is ordinarily required, or in case of undue strains upon the mechanism occurring, as from too sudden starting or other cause; with specially novel provision for making such undue strains operative to stop and save the machine; as is fully set forth in connection with the accompanying drawings and clearly defined in the subjoined claims.

Fig. 1 is a plan view indicating only such portions of a known type of braiding machine as are involved in application of my invention thereto.

Fig. 2 is mainly an elevation looking in the direction of the arrows in Fig. 1.

Figs. 3 and 4 are similar views indicating a modified construction.

The base plate A, drive shaft 8, and drive wheel 5 for operating the carrier mechanism, with its controlling brake drum 6 and band 7, are parts of known braiding machine construction, and are indicated in connection with the particular carrier-operated stop mechanism for effecting automatic stoppage in case of thread breakage; the present invention relating specifically to the added mechanism hereinafter set forth for effecting automatic stopping of the machine in case of undue strains, and to the cooperative arrangement thereof with such known automatic stop mechanism. The clutch device indicated at 11, with stop member 12, its actuating lever 25, and carrier-operated stop mechanism for actuating said lever to automatically release the clutch in case of thread breakage, sufficiently indicate such known mechanism.

As shown in Figs. 1 and 2, a suitable motor indicated at 30, with connected switch 31, are mounted under the base plate A, with the motor shaft 32 arranged to drive the vertical carrier-drive shaft 8^a, under control of the clutch device 11 on horizontal shaft 8, by the broken-thread stop mechanism above referred to. The motor shaft 32 is arranged to drive the horizontally mounted clutch-

equipped shaft 8 by means of a sprocket-wheel drive chain 35 as shown. Under this chain is an idler wheel 36, carried by a lever 37 fixedly pivoted at 38, and pressed against the chain by a lever-connected spring 39 so as to take up slack under normal driving strains, but permit of swinging movement of said lever when the drive chain is tautened by undue strain. Such swinging movement of the lever 37 is suitably arranged to operate the switch 31 so as to stop the motor; this being effected by providing the swinging lever 37 with a switch operating extension 40 (Fig. 2) which engages a rollered-switch lever 41 as indicated.

The modified construction shown in Figs. 3 and 4 illustrates a similar arrangement to Figs. 1 and 2 but having a substitute operating connection of the motor to the carrier-drive and switch mechanisms; a countershaft 50 being employed, which is mounted in carrying arms 51, 51^a swingable on the motor shaft axis with gear connections 52, 53 and 54, 55 provided respectively between the two shafts and between said counter-shaft and the carrier drive shaft 8. In this modified construction the lever 41^a of switch 31^a is operated by an arm 56 on the swingable mounting of said countershaft 50; the latter being normally retained in operating position relative to the motor shaft axis by means of a fixedly pivoted latch 61 which is yieldingly held in engagement with a locking arm 60 on said counter-shaft mounting, by a spring 62. When undue driving strain is exerted the yielding of the spring 62 permits tilting of the latch 61, and swinging movement of the countershaft around the motor shaft axis, whereby the switch lever is operated so as to cut off the motor current as in the Figs. 1, 2 construction previously described.

It will be readily understood that the automatic control of the machine-drive mechanism for preventing the transmission of undue driving strains to the machine, is effected by means of a yielding driving connection substantially as has been fully set forth, in connection with provision for simultaneously freeing the motor by cutting off the motor current, thereby satisfactorily avoiding the

usual dangers of breakage incident to jarring strains. The construction specifically described may obviously be modified within the scope of the invention as defined in the claims.

5 What I claim is:

1. In combination with a braiding machine comprising carrier-drive mechanism; a switch-controlled motor operatively connected to said drive mechanism and to said switch and comprising a transmission unit 10 radially swingable by undue driving strains, and a switch lever operated by said swinging unit to automatically stop the motor.
2. In combination with a braiding machine 15 comprising carrier-drive mechanism; a switch-controlled motor operatively connected to said drive mechanism and to said switch and comprising a drive chain, a spring-pressed idler-wheel lever arranged to regulate the slack of said drive chain, and a switch 20 lever operated by said idler-wheel lever in case of excessive tautening of said drive chain.
3. In combination with a braiding machine 25 comprising carrier-drive mechanism; a switch-controlled motor operatively connected to said drive mechanism and to said switch and comprising a countershaft swingable about the motor shaft and provided with 30 switch-operating and latch-operating arms, and a spring-pressed latch adapted to normally retain said swingable countershaft in operative relation to said carrier-drive mechanism.

35 In testimony whereof I affix my signature.
MAX KRISSIEP.
